UNITED STATES PATENT OFFICE

111,519

DESIGN FOR A BOOKCASE

Herman A. McCune, Boston, Mass.

Application April 1, 1938, Serial No. 76,225

Term of patent 14 years

To all whom it may concern:

Be it known that I, Herman A. McCune, a citizen of the United States of America, residing at Boston, in the county of Suffolk and State of Massachusetts, have invented a new, original, and ornamental Design for a Bookcase, of which the following is a specification, reference being had to the accompanying drawing, forming part thereof, wherein:

The figure is a perspective view of a bookcase, showing my new design.

I claim:—

The ornamental design for a bookcase, as shown.

HERMAN A. McCUNE.
